UNITED STATES PATENT OFFICE.

PAUL SCHMAHL, OF BIBERACH, GERMANY.

WINDOW.

SPECIFICATION forming part of Letters Patent No. 508,348, dated November 7, 1893.

Application filed March 14, 1892. Serial No. 424,865. (No model.)

To all whom it may concern:

Be it known that I, PAUL SCHMAHL, a subject of the King of Würtemberg, residing at Biberach, Würtemberg, Empire of Germany, 5 have invented certain new and useful Improvements in Windows, of which the following is a specification.

This invention relates to an improvement in windows and more particularly to the construction of an upper tilting sash, which may be set so as to admit air either at the top or bottom and which may be manipulated with facility.

It consists in the various features of improvement more fully pointed out in the claims.

In the accompanying drawings: Figure 1 is an elevation of a window provided with my improvement. Fig. 2 is an end elevation of 20 the same; Fig. 3 a face view of the upper sash. Figs. 4, 5 and 6 are end views thereof showing it respectively closed, open at the bottom and open at the top. Figs. 7 to 10 are corresponding views of a modification. Figs. 25 11 to 14 are corresponding views of a further modification; Figs. 15 to 18 corresponding views of a further modification; Fig. 19 a modification of the construction shown in Fig. 14. Fig. 19^a shows a detail of a sash provided with pin *m*. Fig. 20 is a view corresponding to Fig. 18, but with the band *p*, bent. Figs. 21 and 22 are details of the construction shown in Figs. 1 to 6. Figs. 23, 24 and 28 are details of the construction shown 30 in Figs. 7 to 10. Fig. 25 is a detail of the construction shown in Figs. 11 to 14. Figs. 26 and 26^a are details of the construction shown in Fig. 19. Figs. 27 and 30 are modifications of the details shown in Figs. 21 and 40 22. Figs. 29 and 29^a are details of the construction shown in Figs. 15 to 18.

The letter *c*, represents the upper sash provided with sash bolt *a*, or snacket *a'*, that engages the frame *b*, while *c'*, *c*, are the lower hinged sashes. At the top, the sash *c*, is provided with a pair of buttons *f*, *g*, to which are attached strings *s*, *s'*, passing through suitable eyes on the frame *b*, and adapted to be secured at the lower end to a button *k*. To 45 the side rails of sash *c*, there are secured the eyes *d*, engaged by the inner ends of bent rods *e*, the outer ends of which are received

by corresponding eyes *d'*, secured to frame *b*. (See Figs. 21 and 22.)

To open the sash *c*, the bolt *a*, is disengaged 55 and the strings *s*, *s'* released from knob *k*. This will cause the sash *c*, to be lowered by its own weight and to swing outward at its lower end, to assume the position shown in Fig. 5. The outer bent end *x* (Fig. 21) of rod 60 *e*, striking against the eye-forming plate, prevents the sash from dropping down beyond the pre-determined point.

A curtain *r*, secured to the upper rail of the window frame will overlap the upper edge of 65 sash *c*, so that the air is admitted at the bottom but excluded at the top.

To reverse the sash *c*, a knob *q*, Fig. 5, is pressed toward the frame, which will cause the sash to tilt on its rod *e*, and to assume the 70 position shown in Fig. 6, where the air is admitted at the top but excluded at the bottom. In Figs. 27 and 30 the inner end *x'*, of bar *e*, prevents the sash *c*, from dropping.

In Figs. 7 to 10 and 23, 24 and 28, a pin *d*², 75 secured to the sash *c*, is engaged by the elongated slot of a bracket *e'*, attached to frame *b*. The sash may readily be tilted in either direction and is open when the pin occupies the forward end of the elongated slot. 8c

In Figs. 11 to 14 and 25, a screw hook *e*², engages the eye *d*, secured to sash *c*.

In Figs. 19, 26 and 26^a, the hook *e*², terminates in an eye *e*³, that engages a screw pin *e*⁴, inserted into sash *c*. 85

In Figs. 15 to 18, 20, 29 and 29^a, a lower band *p*, has been added for receiving a pin *x*², projecting from the lower end of the sash. The band *p*, may either be plain as in Fig. 29^a, or provided with a set of seats *p'*, as in Fig. 90 29, for locking the sash in various positions.

In Fig. 19^a the upper edge of the sash is shown to be provided with a laterally projecting pin *m*, engaging a groove of frame *b*, and which is used to hold the sash to the frame. This construction is used when the rabbit is of such a form as not to perform this function.

What I claim is—

1. In a window or door frame, the combination with the swinging sash *c*, having its upper and lower ends free to swing in and out of said frame, a pair of arms projecting from the window frame to which the sash is piv-

otally secured, and a pair of operating cords, one end of each being attached to the upper rail of the sash, and the other ends of which are attached to the window frame, one of said 5 cords being adapted to raise the sash in its closed position, while upon releasing the other the sash will be lowered or opened by its gravity, substantially as described.

2. In a window or door frame, the combination of the sash *c*, operating ropes *s*, *s'*, a pair 10 of arms projecting from the window frame to which the sash is pivotally secured, and a rolling curtain fastened to the upper part of the window frame, the free end of said cur-

tain being detachably secured to the sash, 15 substantially as described.

3. The combination of sash *c*, with ropes *s*, *s'*, arms for pivotally connecting the same to the window frame and with a band *p*, for receiving the lower end of the sash, substantially as specified. 20

Signed at Stuttgart, Würtemberg, this 23d day of February, 1892.

PAUL SCHMAHL.
